DESIGN FOR A NEBULIZER

Ralph G. Cheney and Benjamin S. Paschall, Seat-
tle, Wash; said Cheney assignor to said
Paschall

Application July 3, 1942, Serial No. 107,404

Term of patent 14 years

To all whom it may concern:

Be it known that we, Ralph G. Cheney and Benjamin S. Paschall, citizens of the United States of America, both residing at Seattle, in the county of King and State of Washington, have invented a new, original, and ornamental Design for a Nebulizer, of which the following is a specification, reference being had to the accompanying drawing, forming part thereof.

Figure 1 is a side elevational view of a nebulizer showing our new design with the stoppers removed;

Figure 2 is a front elevational view of the nebulizer with the stoppers fitted into the ports of the reservoir;

Figure 3 is a top perspective view of our nebulizer.

The nebulizer is made of transparent material, such as a suitable plastic substance, so that the interior of the container is visible. The dominant features of the design reside in the portions shown in full lines.

We claim:

The ornamental design for a nebulizer, as shown and described.
